JAMES T. COWLEY, OF SYRACUSE, NEW YORK, ASSIGNOR TO THE LAMSON COMPANY,
OF SYRACUSE, NEW YORK, A CORPORATION OF MASSACHUSETTS

PNEUMATIC DISPATCH TUBE SYSTEM

Application filed September 30, 1929. Serial No. 396,063.

This invention relates to an improvement in pneumatic dispatch tube system of the minimum flow type. In such a system the transmission tube is supplied with power through a continuation of the tube which leads to a source of negative pressure, such for example as a vacuum drum or header. The vacuum pressure in the transmission tube is regulated by a valve located in such continuation tube, and it has heretofore been the practice to provide a power control which operates directly upon such valve in response to the various conditions set up in the transmission tube. Such practice renders it necessary to provide a power control element especially constructed for each size of tube.

The primary object of this invention is to provide a separate power control unit which may be attached to continuation tubes of various diameters for opening and closing the valves in the tubes.

Other objects will appear from a consideration of the following specification taken in connection with the drawings which form a part thereof, and in which:

Fig. 1 is a plan view of a portion of a continuation tube provided with a power control unit;

Fig. 2 is a sectional view taken along the line 2—2 of Fig. 1;

Fig. 3 is a side elevation of the construction shown in Figs. 1 and 2, the relation of the valves of the tube and unit being indicated by dotted lines; and

Figs. 4 and 5 are sectional views illustrating the power control unit with the valve in opened and closed positions.

In the drawings the reference numeral 10 designates a tube which forms a continuation of the transmission tube, not shown, connecting it to the source of negative power, also not shown. The tube 10 has an axially extending passage 11 in which is mounted a valve 12 of the butterfly type carried on a shaft 13. The shaft 13 is supported in bosses 14 on the tube with its ends projecting beyond the bosses for reasons to be pointed out below. In one wall of the tube 10, above and below the valve 12, are provided orifices 15 and 16.

Securely mounted upon one side of the tube 10 is a power control unit 20 having an operative element which may be of any desired type. For the purpose of this invention, however, I have elected to show herein the type of power control element disclosed in my copending application, Serial No. 317,857, filed November 7, 1928. The unit 20 comprises the power control element 21 connected by conduits 22, 23 to the orifices 15 and 16 in the wall of the tube 10. The element 21 may be briefly described as comprising a tube 25 having an axial passage in which is mounted a valve 26 carried by a shaft 27. The position of the valve 26 is controlled by a plurality of pneumatics 28, 29. By the term "pneumatic" it will be understood that I designate broadly any pressure or vacuum instrumentality, such as for instance a flexible diaphragm, piston, or bellows by which fluid pressure is converted into mechanical motion.

The pneumatic 28 acts to reciprocate a rod or stem 30 having a reduced end portion 31 which passes through an aperture 32 in the valve 26. The difference in diameter between the two portions of the stem 30 provides a shoulder 33, and mounted upon the reduced portion 31 is a collar 34. The shoulder and collar are, as is clearly shown in Figs. 4 and 5, on opposite sides of the valve 26. The shoulder 33 acts, when the pneumatic 28 is in one position, to initiate the opening of the valve as shown in Fig. 4 and the collar 34 acts, when the pneumatic 28 is in the other position, to initiate the closing of the valve 26. The pneumatic 29 operates a rod 35 carrying a valve 36 which controls a port 37 connecting the housing of the pneumatic 28 with the passage in the tube 25. A by-pass 38 controlled by a screw 39 acts with the aperture 32 to provide a continuous minimum flow of air through the passage without disturbing the pneumatics which normally assume the positions shown in Fig. 5.

The shafts 27 and 13 are preferably though not necessarily in axial alignment. Mounted upon the end of the shaft 27 adjacent the tube 10, is an arm 40 having at its

upper end a notch or recess 41. Mounted upon the end of the shaft 13 adjacent the tube 25 is an arm 42 which terminates in an outwardly projecting bar 43. The bar 43 enters the notch 41 in the arm 40 and since the notch 41 is preferably made wider than the bar 43, a certain amount of play is provided for reasons to be described below. Fixed on the other end of the shaft 13 is an arm 45 provided at its lower end with a screw 46 adapted, when the valve 12 is closed, to bear against a stop 47 which may be, as here shown, a projection upon the wall of the tube 10.

The conduits 22 and 23, connecting the orifices 15 and 16 of the tube 10 with the tube 21, provide passages through which, when the valve 12 is closed, as shown in Fig. 3, air is bypassed from the tube 10 through the tube 21. The air passes into the tube 25 from the tube 10 through the orifice 15 and conduit 22, through the aperture 32 and port 38 into the conduit 23 and thence, through the orifice 16 into the tube 10 below the valve. When, however, a carrier is inserted into the transmission line, the minimum flow is substantially cut off so that the pressure of air in the system is reduced. This reduction of the pressure acts through the port 37 upon the pneumatic 28, causing it to shift from the position shown in Fig. 5 to that shown in Fig. 4. The pneumatic 29 then shifts into the Fig. 4 position closing the port 37. This movement of the pneumatic 28 causes the shoulder 33 of the stem 30 to bear against one face of the valve 26 shifting it from its closed position. The air rushing through the tube 21 completes the opening of the valve. By reason of the connection between the shaft 27 of the valve 26 and the shaft 13 of the valve 12, this movement of the valve 26 causes the valve 12 to open, thus providing a free passage for the air through the tube 10 and permitting the creation of the necessary pressure in the transmission tube to impel the carrier from one station to another.

After a predetermined interval the pneumatic 28 will resume the position shown in Fig. 5, carrying with it the valve 26 and thus closing the valve 12. Subsequent thereto the pneumatic 29 moves into the Fig. 5 position opening the port 37. Should this take place while a carrier is in transit the valve 12 will be automatically reopened as pointed out above. The amount of play provided between the bar 43 and notch 41 permits the valve 12 to start to open and to resume its seat after the valve 26. This eliminates the necessity for extreme care in adjusting the operation of such valves. Moreover the opening of the valve 26 is largely performed by the rush of air after the initiation of such movement and thus more power is provided to move the valve 12 from its closed posi-

tion than would be the case if the valves moved simultaneously.

The construction above described and shown in the drawings thus provides in combination with the valved continuation tube of a minimum flow pneumatic dispatch system a control unit by which the valve of the tube is caused to move in response to the status of the air in the transmission line. Moreover the unit may be employed with tubes of various diameters so that it can be made in quantities and so that the need which previously existed of providing a control for each diameter of tube is eliminated. It will be understood that I am not limited to the particular details of structure and operation set forth in the illustrative embodiment since other embodiments might be made without departing from the spirit and scope of the invention as set forth in the following claims.

I claim:

1. In a pneumatic dispatch tube apparatus of the minimum flow type, the combination with the continuation tube thereof having a valve therein, of a control unit responsive to the status of the air in the transmission line including a valve, and means positively actuated by the valve in the unit for opening or closing the valve in the continuation tube. 90
2. In a pneumatic dispatch tube apparatus of the minimum flow type, the combination with the continuation tube thereof having a valve therein, of a control unit responsive to the status of the air in the transmission line, a valve in said unit and means connecting said valves whereby the opening and closing of the valve in the unit causes the opening and closing of the valve in the tube. 95
3. In a pneumatic dispatch tube apparatus of the minimum flow type, the combination with the continuation tube thereof having a valve therein, of a control unit responsive to the status of the air in the transmission line, a valve in said unit and a connection between said valves, which connection provides considerable play whereby the valve in the continuation tube is opened and closed after the valve in the unit is opened and closed. 105
4. In a pneumatic dispatch tube apparatus of the minimum flow type, the combination with the continuation tube thereof having a valve therein, of a control unit responsive to the status of the air in the transmission line, a valve in said unit and a connection between said valves, whereby the valve in the continuation tube is opened and closed after the valve in the unit is opened and closed. 110
5. In a pneumatic dispatch tube apparatus of the minimum flow type, the combination with the continuation tube thereof having a valve therein, of a control unit responsive to the status of the air in the transmission line, 115

a valve in said unit, conduits connecting said unit and tube above and below the valves therein, means in the unit providing a bypass around its valve whereby said unit acts as a bypass when the valve in the tube is closed, the valve in the unit opening and closing in response to the status of the air and means causing the valve in the unit to open and close the valve in the tube.

10 6. In a pneumatic dispatch tube apparatus of the minimum flow type, the combination with the continuation tube thereof having a valve therein, of a control unit responsive to the status of the air in the transmission line, a valve in said unit, conduits connecting said unit and tube above and below the valves therein, means in the unit providing a bypass around its valve whereby said unit acts as a bypass when the valve in the tube is closed, the valve in the unit opening and closing in response to the status of the air, means for initiating the opening and closing movements of the valve in the unit and a connection between the valves causing the valve in the unit to open and close the valve in the tube.

7. In a pneumatic dispatch tube apparatus of the minimum flow type, the combination with the continuation tube thereof having a valve therein, of a control unit responsive to the status of the air in the transmission line, a valve in said unit, conduits connecting said unit and tube above and below the valves therein, means in the unit providing a bypass around its valve whereby said unit acts as a bypass when the valve in the tube is closed, the valve in the unit opening and closing in response to the status of the air, pneumatic means for initiating the opening and closing movements of the valve in the unit and a connection between the valves causing the valve in the unit to open and close the valve in the tube.

8. In a pneumatic dispatch tube apparatus of the minimum flow type, the combination with the continuation tube thereof, a transversely extending shaft in said tube and a valve upon said shaft, of a control unit responsive to the status of the air in the transmission line, said unit having a passage therethrough, conduits connecting said passage with the tube above and below the valve therein whereby the passage acts as a bypass when the valve is closed, automatically acting means for controlling the flow of air through said bypass and a connection from said means to said valve for opening said valve when said bypass is open and closing said valve when said bypass is restricted.

60 9. In a pneumatic dispatch tube apparatus of the minimum flow type, the combination with the continuation tube thereof, a transversely extending shaft in said tube and a valve upon said shaft, of a control unit responsive to the status of the air in the

transmission line, said unit having a passage therethrough, conduits connecting said passage with the tube above and below the valve therein whereby the passage acts as a bypass when the valve is closed, a shaft extending 70 transversely of the passage, a valve on said shaft, automatic means for causing the valve to regulate the flow of air through the bypass and a connection between said shafts whereby the valve in the unit operates the 75 valve in the tube.

Signed by me at Boston, Massachusetts, this 27th day of September, 1929.

JAMES T. COWLEY.
